UNITED STATES PATENT OFFICE.

LEONARD B. BUCHANAN, OF WOBURN, MASSACHUSETTS, ASSIGNOR TO CHASE-SHAWMUT COMPANY, OF NEWBURYPORT, MASSACHUSETTS, A CORPORATION OF MASSACHUSETTS.

ELECTRIC FUSE.

1,246,711.

Specification of Letters Patent. Patented Nov. 13, 1917.

Application filed December 7, 1914, Serial No. 875,752. Renewed April 14, 1917. Serial No. 162,188.

To all whom it may concern:

Be it known that I, LEONARD B. BUCHANAN, a citizen of the United States, residing at Woburn, in the county of Middlesex and State of Massachusetts, have invented an Improvement in Electric Fuses, of which the following is a specification.

This invention relates to an improved indicator-device for inclosed electric fuses of a type adapted to show conspicuously by the displacement of an indicator element visible at the outside of the fuse, when the fuse is blown out. The prime object of the invention is to provide an indicator-device of a simple, reliable, and effective kind that is not attached to the fuse-wire or strip, and consequently capable of quick and convenient assemblage with the other parts in the fuse-holder. To this end I provide an indicator-member mounted so as to be visible at the outside of the fuse-shell, which is normally held in one position, in readiness to act, by a connection with a mass of material of a nature to be disintegrated by the heat incident to a blow-out, said visible indicator-member then moving to change its position conspicuously to denote the blow-out. This mass of material to be disintegrated by the heat of the blow-out, is, in accordance with the present invention, held in a separate compartment from the true fuse-wire but in such proximity to a high resistance shunt which is blown by the blowing of the true-fuse that the heat therefrom will explode said mass of material which may be gun-cotton or like material of a gas-producing nature that is quickly and completely disintegrated by the degree of heat evolved in the blow-out. The foregoing and other objects and features of the invention will be better understood from the following detailed description taken in connection with the accompanying drawings.

Figure 1, is a view partly in elevation and partly in lengthwise section of a fuse having an indicator-device embodying my invention.

Fig. 2, is an enlarged sectional detail of the indicator-device.

Fig. 3, is a detail elevation showing the indicator elements detached; and,

Fig. 4, is a transverse section through a fuse showing a slightly modified form and arrangement of the indicator element.

The invention is herein, for illustrative purposes, shown as embodied in a type of fuse, such as shown in Letters Patent #801,467, dated October 10, 1905, it having a true fuse-strip or wire 10, extended centrally lengthwise through the fuse-shell 11, 60 and connected to the metallic end-caps 12; and a high resistance shunt-wire 13, extending from end to end of the fuse connected with the end-caps thereof and lying along the side of the fuse-shell. This shunt-wire 65 13, should be made of high resistance material, such as fine German-silver wire, so as to carry only a trivial part of the current, and not be unduly heated until heated by the transfer of the current thereto when the fuse-strip 10 has melted or vaporized. In accordance with my invention, means is provided within a separate compartment through which the shunt-wire passes in proximity to the shunt-wire above referred 70 to but not in any way connected with or restrained, thereby adapted to be exploded by the heating thereof, to release or cause a change in position of a member visible outside the fuse-body. The member thus conspicuously visible outside the fuse-body is shown as a spring-strip 14, fixed at one end to the body or shell, as at 15, and its free end tending to normally spring outward, as seen in dotted lines in Fig. 1. This spring-strip 85 14, is, however, normally held down close to the shell by a fastening-device, such as a fine thread or filament 16 which is wound around or tied, or otherwise connected, to a mass of material 17, such as gun-cotton, which is 90 quickly disintegrable by the heat of the fuse-wire upon a blow-out. The mass 17 is itself held in a wire-gauze thimble or cap 18, that is set into a hole 19, therefor, through the fuse-case and held therein. Washers or pads 95 20 of fiber or stiff textile may be placed at each side of the mass 17, to hold it confined in the thimble 18, and assist in preventing the heat of the arc from forcing its way through the opening in the fuse-case. Thus 100 it will be noted that the mass of combustible and disintegrable material 17 is held in the thimble 18 in close proximity to the additional or shunt-wire 13, and that the indicator-strip 14 will be held down close to 105 the shell, in a relatively inconspicuous position, so long as the gun-cotton is not set off and consumed. As soon, however, as the

fuse blows out, and the resistance shunt-wire 13 becomes in consequence highly heated, the mass of gun-cotton 17 will be disintegrated and the thread 16 therefor released, permitting the indicator 14 to spring out to a relatively conspicuous position, showing that the fuse has blown out. In addition there will be a slight smoke and noise at the indicator which will call the attention 10 of the blowing of the fuse to anyone in the vicinity. In Fig. 4 the indicator-strip 14', instead of extending lengthwise of the shell, as shown in the preceding figures, is curved around the shell, through some little arc, to 15 obtain the necessary resilient spring-out action.

I claim:—

An electric-fuse comprising a casing, a 20 fuse-wire extended therein, and means for indicating the blowing of said fuse consisting in a spring attached to the outside of said casing having a portion adapted to

move away from said casing when released, a fastening-device for holding said spring in retracted position, said fastening-device 25 being attached to said spring, and a mass of material to which said fastening-device is also attached, which is arranged within the fuse-case and is disintegrable by heat, a high resistance shunt-wire within the fuse-case 30 arranged in proximity to said mass of material but not connected with the same or tending in any way to hold said spring under restraint, the blowing of the shunt-wire causing disintegration of the mass of material and consequent release of the spring, substantially as described.

In testimony whereof, I have signed my name to this specification, in the presence of two subscribing witnesses.

LEONARD B. BUCHANAN.
